[57] **CLAIM**

The ornamental design for the combined stamp pad and support, as shown and described.

DESCRIPTION

FIG. 1 is a top plan view of a combined stamp pad and support showing my new design, the broken lines depicting a stamp pad container being for illustrative purposes only and forming no part of the claimed design;

FIG. 2 is a perspective view thereof; the broken line showing of environmental matter is for illustrative purposes only and forms no part of the claimed design;

FIG. 3 is a side elevational view thereof, with the opposite side being identical to the side shown; and,

FIG. 4 is an end elevational view thereof, with the opposite side being identical to the end shown.
